HANDLE FOR A SCRAPER

Mal Roy Henderson, Wichita, Kans.

Application March 9, 1956, Serial No. 40,534

Term of patent 14 years

(Cl. D9—8)

Fig. 1 is a side elevation of a handle for a scraper showing my new design; and

Fig. 2 is an end elevation of same.

The broken line showing of a scraper in both of the figures is for illustrative purposes only.

I claim:

The ornamental design for a handle for a scraper, substantially as shown and described.
